UNITED STATES PATENT OFFICE.

HODGSON S. PIERCE, OF DETROIT, MICHIGAN, ASSIGNOR TO THE STUDEBAKER CORPORATION, OF SOUTH BEND, INDIANA, AND DETROIT, MICHIGAN, A CORPORATION OF NEW JERSEY.

TOP CONSTRUCTION.

Application filed January 7, 1925. Serial No. 1,044.

This invention relates to tops for motor vehicles and the like and particularly to tops of the permanent type, and constitutes an improvement over the construction shown 5 and described in the application of Joseph H. Bourgon on top construction filed November 20, 1924; Serial Number 751,154.

One of the objects of the present invention is to provide a top of novel and improved 10 construction, the main portion of which is composed of sheet metal to make it strong and durable and to which other parts and members may be applied to form a permanent unitary structure.

Another object is to provide a top frame 15 constructed mainly from a continuous sheet of metal having a sound absorbing or deadening lining therein so that the top of which it forms a part will not be subject to the 20 drumming usually associated with tops of this type.

Another object is to provide a vehicle top frame constructed from a continuous sheet of metal and provided with a sound absorbing 25 or deadening lining, the upper portion of the top frame being provided with a plurality of openings, and the metal displaced in the forming of the openings being formed to clamp the lining in place against the top 30 frame.

A further object is to provide a vehicle top frame composed of a continuous sheet of metal provided with a lining of sound absorbing or deadening material, relatively 35 large matching openings being provided in both the sheet metal and the lining, a portion of the metal displaced in forming the openings in the sheet metal portion being bent back on itself to clamp the lining adjacent the openings therebetween, and another portion being downwardly bent to form 40 attaching flanges for cross ribs or tacking strips.

The above being among the objects of the 45 present invention, the same consists of certain features of construction and combinations of parts to be hereinafter described with reference to the accompanying drawing, and then claimed, having the above and other 50 objects in view.

In the accompanying drawing which illustrates a suitable embodiment of the present invention, and in which like numerals refer to like parts throughout the several views:—

55 Figure 1 is a perspective view of a finished

automobile top, constructed in accordance with the present invention, mounted upon an open type automobile body.

Figure 2 is a perspective view of the top frame for the top shown in Figure 1. 60

Figure 3 is an enlarged fragmentary perspective view of a portion of the frame in Figure 2, taken through one of the openings in the frame and showing the manner in which the metal at the edge of the opening 65 is bent back on itself to secure the sound absorbing lining in place, and also showing the cross ribs or tacking strips for the top finishing lining secured in place.

Figure 4 is a transverse sectional view of 70 the frame of Figure 2 taken through two of the openings.

Figure 5 is a longitudinal sectional view of the frame of Figure 2, taken through one of the rows of openings. 75

The top frame as shown in Figure 2 is formed preferably from a single continuous sheet of metal into the desired shape and contour, but in the following description and claims which will refer to the top frame as 80 being constructed from a continuous sheet of metal, it will be kept in mind that the present invention is not limited to a metal top frame which is constructed from a single sheet of metal, as it is applicable to and includes those constructions where the same are made up of a plurality of units welded, riveted or otherwise suitably secured together to form a continuous sheet, and has the same practical results and effects as a 85 frame constructed from a single sheet.

Top frames constructed from a continuous sheet of metal have had but a limited use in the past due to the fact that these early designs had a tendency to vibrate in 90 unison to a highly objectionable degree with other vibrations present in the automobile of which they formed a part, or with the explosions of the engine, in much the same way that a drum head may be made to vibrate 95 in sympathy with independent vibrations. Such vibrating of the top is commonly known as "drumming," and in the present invention a construction is provided that effectually eliminates this objection as it appeared in the tops heretofore used. 100

As above mentioned, the metal of the top frame 10 is formed from a continuous sheet of metal into the desired shape and contour, that is, to the shape of conventional tops 110

as shown in Figures 1 and 2, or otherwise, but preferably such that no flat spots are present anywhere on its surface to better eliminate any drumming sound that may 5 develop. As illustrated in Figures 2 and 5, wooden front cross member 11 is provided in the construction shown to more easily secure a rainshield 12 or windshield 13 there-
 to, but this may be dispensed with and the 10 metal of the top 10 be extended to take its place. At frequent intervals in the upper and flattest surface of the frame 10 relatively large openings 14 are provided which tend to prevent the drumming of the top with the 15 same result as is experienced when openings are cut in a drum head, that is, if the openings 14 are large enough they will substantially eliminate the greater part, if not all, of the vibrations in the top. In forming 20 the openings 14, the metal adjacent the edge thereof displaced in the operation of forming of the same is bent downwardly in the form of a flange 15 (see Figure 3) for a purpose to be hereinafter described.
 25 Against the under surface of the frame 10 is placed a sheet of sound absorbing or sound deadening material 16. This may be of any suitable material such as a relatively thick sheet of wood pulp formation, felt forma-
 30 tion or other material which will have the same sound absorbing effect. This sheet 16 may be formed to completely cover the interior of the frame 10, but in the drawings as shown in Figures 4 and 5 it is shown as ex-
 35 tending only a short distance into the curved side and end portions, this being considered all that is practically necessary in view of the fact that it is the flat top portion of the frame 10 that is subject to the drumming 40 sounds. The sheet 16 is provided with openings therein matching the openings 14 in the frame 10 and is placed in matching relation therewith and preferably glued in place over the entire matching surface.
 45 When the sheet 16 is thus placed in position, the downwardly turned metal flanges 15 around the edges of the openings 14 project through the openings in the sheet 16 and are bent back over the edge of the sheet 16, as 50 shown in Figure 3, thus clamping the sheet 16 tightly against the inner surface of the frame 10 and thereby securely holding it in place against the frame 10. If the sheet 16 is of sufficiently rigid material and the 55 edges are extended over onto the curved side portions of the frame 10 as shown in the drawings, not only will it act to deaden or absorb any drumming that may tend to be set up in the top, but it will also add to the 60 stiffness and strength of the top due to the necessity of springing the sheet to bring it into contact with the frame 10 over its entire surface.

It is preferable that a portion of the flange 65 15 be split vertically from the rest of the

flange and left to project downwardly as at 17 in Figure 4 to provide a flange for at-
 taching a wooden strip such as 18 thereto, the wooden strip 18 acting either as a trans-
 verse strengthening rib or as a tacking strip 70 for the top inner finishing lining 19, or as both. The strip 18 may be further secured in place by screws such as 20 passing vertically through the frame 10 and sheet 16 into the same. 75

It is further desirable that the lower edges of the frame 10 be turned inwardly to provide a horizontally extending flange 21 to which may be secured a tacking strip 22 for the top outer covering. 80

The frame 10 and its integral parts may be utilized in conjunction with any suitable type of vehicle, either of the open or closed type, but in Figure 1 a modification of the same is shown mounted on an open type of 85 automobile body 23 by front supports 24 and rear supports 25, the rear supports 25 and a suitable back sheathing being secured there-
 to so that they may be assembled as a unit with the top to the body 23. 90

Formal changes may be made in the specific embodiment of the invention described without departing from the spirit and substance of the broad invention, the scope of which is commensurate with the appended 95 claims.

What I claim is:—

1. In a vehicle top, a metal frame having a substantially horizontal top portion, integral curved sides, and a curved rear portion, sound absorbing material secured to said frame top portion, matching openings extending through said frame top and said material, the metal displaced in forming the openings in said frame forming securing means for said material and a depending flange, a tacking strip secured to said flange and a lining secured to said tacking strip to conceal the same, said material and said openings. 100

2. A frame for a vehicle top formed from a continuous sheet of metal and lined with a sound deadening material, matching openings in said sheet metal and said material, a portion of the metal displaced in forming the openings in said sheet of metal being bent out of the plane of said sheet, to secure said sound deadening material thereto and to form an attaching flange, a tacking strip secured to said flange, and a lining secured to said tacking strip. 115

3. A frame for a vehicle top formed from a sheet of metal and being provided with a sheet of sound absorbing material secured to the under surface thereof, matching openings in said sheet of metal and said material, a portion of the metal displaced in forming the openings in said sheet of metal being bent down and back on itself to clamp said material therebetween, and another por- 125

tion being bent downwardly to form an attaching flange.

4. A frame for a vehicle top having a continuous sheet metal top portion lined with a sheet of sound deadening material, said sheet metal and said material being provided with a plurality of matching openings, a portion of the metal displaced in forming the openings in said sheet metal being bent downwardly to a point below said material

and then back on itself thereby clamping said material against said sheet metal, another portion of said displaced metal being bent downwardly to form attaching flanges, and transverse cross members secured to said flanges. 15

Signed by me at South Bend, Indiana, U. S. A., this 30th day of December 1924.

HODGSON S. PIERCE.
